UNITED STATES PATENT OFFICE

154,191

DESIGN FOR A PORTABLE BEVERAGE
DISPENSER

Burton O. Smith, Chicago, Ill., assignor to Vacuum Can Company, Chicago, Ill., a corporation of Illinois

Application June 8, 1948, Serial No. 146,831

Term of patent 14 years

(Cl. D2—3)

To all whom it may concern:

Be it known that I, Burton O. Smith, a citizen of the United States, residing at Chicago, in the county of Cook and State of Illinois, have invented a new, original, and ornamental Design for a Portable Beverage Dispenser, of which the following is a specification, reference being had to the accompanying drawings, forming part thereof.

Figures 1 and 2 are front and rear perspective views, respectively, of a portable beverage dispenser embodying my new design.

I claim:

The ornamental design for a portable beverage dispenser, substantially as shown.

BURTON O. SMITH.
